PLASTIC OVERTSHOE

Duncan E. Slade, Naugatuck, Conn., assignor to United States Rubber Company, New York, N.Y., a corporation of New Jersey

Filed Dec. 18, 1959, Ser. No. 58,712

Term of patent 14 years

(Cl. D7—7)

Fig. 2

Fig. 2

Fig. 3

Fig. 1 is a three-quarter side perspective view of a plastic overshoe, showing my new design;

Fig. 2 is a side perspective view of the opposite side thereof; and

Fig. 3 is a rear perspective view thereof as it appears with a top slightly spread out.

My design is characterized by the band of contrasting texture around the top of the plastic overshoe where in one side of the grooves forming the band has a highly lustrous reflective surface so as to present an iridescent effect substantially as shown.

I claim:

The ornamental design for a plastic overshoe, substantially as shown and described.
